(57) **CLAIM**

The ornamental design for a bicycle shoe cleat, as shown and described.

DESCRIPTION

FIG. 1 is a bottom, rear, right perspective view of a bicycle shoe cleat showing my new design;

FIG. 2 is a top, rear, left perspective view thereof;

FIG. 3 is a rear view thereof;

FIG. 4 is a front view thereof;

FIG. 5 is a right view thereof;

FIG. 6 is a left view thereof;

FIG. 7 is a bottom view thereof;

FIG. 8 is a top view thereof;

FIG. 9 is a front view thereof, shown in a position of use on a shoe;

FIG. 10 is a left view thereof, shown in a position of use on the shoe; and,

FIG. 11 is a left, front, top view thereof, shown in a position of use on the shoe.

The broken line showing of the shoe is for the purpose of illustrating the bicycle shoe cleat in a position of use. The broken lines form no part of the claimed design.
